UNITED STATES PATENT OFFICE.

JOHN B. TERRY AND RALPH A. HALLORAN, OF BERKELEY, CALIFORNIA, ASSIGNEES,
BY MESNE ASSIGNMENTS, TO STANDARD OIL COMPANY OF CALIFORNIA, OF LOS
ANGELES, CALIFORNIA, A CORPORATION OF DELAWARE.

PROCESS FOR PRODUCING LUBRICATING OIL FROM PETROLEUM OIL.

No Drawing. Application filed February 14, 1923, Serial No. 619,012. Renewed May 16, 1928.

This invention relates to a process for producing lubricating oil and other valuable products from asphaltic residue obtained by the distillation of crude petroleum.

5 Asphalt is the residuum obtained by distilling petroleum oil of an asphaltic or mixed base crude. Such residuum cannot normally be distilled, even under vacuum and with the use of steam, without decomposition of the 10 lubricating fractions it may contain. The distillation of such asphalt produces a distillate having a relatively small percentage of viscous bodies suitable for lubricating purposes, and even such viscous bodies as are 15 present in the distillate are mixed with undesirable cracked fractions which are expensive to remove.

We have discovered that when such residual asphalt is heated to a decomposing temperature and preferably a material portion 20 of the asphalt destructively distilled off that the residuum of such treatment has undergone a marked change in properties. While normally asphalt is substantially entirely 25 soluble in light petroleum distillates, the residuum following the decomposition treatment is readily separated by light petroleum distillates into an insoluble brownish powder, and an extract of a heavy viscous lubricating 30 oil which is substantially free of asphalt and readily refined for the production of high grade lubricating oil.

We have further discovered that the extract of such decomposed asphalt can be 35 readily treated and will yield petrolatum or high melting wax, which products are normally not commercially recoverable from asphaltic base crudes.

The objects and advantages of this invention 40 will be readily understood from the hereinafter described process which is given as a preferred example of a process embodying the invention. The invention is not limited to such preferred example but may be modified and embodied in numerous forms.

We prefer to charge crude oil into a still 45 or a series of stills, and distill the crude oil until the residuum or asphalt has been reduced, as far as can be practically carried out 50 without destructive distillation of the very high boiling products being distilled off at this point. For this purpose high vacuum and steam should preferably be employed during the fractionation of the high boiling

point oils, so that a maximum production of 55 uncracked high boiling viscous bodies may be obtained.

When this degree of distillation of the crude oil has been reached, further distillation will result in a distillate which contains 60 increasing percentages of decomposed fractions which are low boiling and relatively non-viscous and the distillate is comparatively 65 of slight value as a source of viscous products.

The degree of distillation which can be carried out without decomposition taking place will vary with the crude oil being treated. With a familiar grade of California crude, the crude may be advantageously distilled until 70 the residual asphalt obtained gives a penetration of approximately 70 as determined by the usual method.

In the next stage of the process whether the asphalt is produced by the preferred 75 process or any other, or whether or not the asphalt is reduced to such penetration test given as an example, asphalt is distilled with an accompanying decomposition until the residuum of such asphalt is converted into 80 substantially two constituents, i. e. viscous, high boiling oil and a brownish powder insoluble in light petroleum distillates. Such distillation of the asphalt may be carried out with the aid of vacuum and steam, to assist 85 the vaporizing of the distillate, but essentially the distillation must be conducted with a substantial cracking of distillate. The distillate throw over will be of relatively low boiling point and low viscosity, and will constitute an inferior stock for the production of 90 lubricating oils. Such distillate may be readily used as fuel oil.

The degree to which the distillation of the asphalt should be carried out varies with the 95 nature of the asphalt distilled and the relative proportions desired of the fuel oil, and thereafter produced lubricating oil. The degree of distillation of the asphalt thus varies with choice of the refiner, but the distillation 100 must be conducted until the residuum or pitch will yield with light petroleum distillates a substantially asphalt-free extract of lubricating oil, and the distillation should not be continued until the asphalt 105 begins to coke. We prefer to continue the distillation until the pitch in the still is still liquid at the high temperature employed, but

if some ten percent more of the pitch were distilled off, the residuum would then be no longer liquid, but would become a granular, coky, semi-liquid substance, which is the first stage of coking as known to the art. We refer to the pitch produced by our preferred operation as aforesaid as "near coke".

When using a familiar 70 penetration asphalt, the distillation of approximately 50 percent of the asphalt will result in the described pitch. The preferred pitch when drawn from the still and cooled, is of a brittle, flinty character, not sticky at normal temperatures. Such pitch is characterized by a melting point having a ball and ring test of higher than 200 degrees Fahrenheit, and is also characterized as having a solubility in 86 Baumé gravity gasoline, as determined by the method given in Richardson's—"The Modern Highway" published by Wiley & Sons of not in excess of 65 percent.

The following figures illustrate an example of an analysis of a pitch found suitable for the extraction of lubricating oil.

25	Specific gravity	1.424
	Penetration	2
	Melting point	240°F.
	Soluble:	
30	(a) Carbon bisulphide	90.6%
	(b) Carbon tetrachloride	69.48%
	(c) 86 Bé. gasoline	52.3
	Fixed carbon	27.95
	Free carbon	9.38

35 The pitch may be produced by the preferred process or in one single distillation from petroleum. However, produced, the pitch is mixed with a solvent oil. More efficient results may be obtained if the pitch is mixed 40 with the solvent while still somewhat heated. The solvent oil used should be in a ratio of at least one part of solvent to two parts of pitch and not in excess of ten parts of solvent to one part of pitch. About two parts of solvent 45 oil to one part of pitch, have produced the most satisfactory results. For the solvent oil we prefer a relatively low boiling petroleum distillate which has a mean boiling point of less than 500 degrees Fahrenheit. The 50 solvent used should not contain a large percentage of aromatic constituents, since aromatic oils such as benzol dissolve the brownish powder which is intended to be separated from the oil constituents of the pitch.

55 Alcohol (methyl or ethyl) with ethyl ether or benzol, higher alcohols such as propyl, butyl, and amyl and combinations of any or all such compounds, all of which may be adjusted to have about the same solvent power 60 with regard to asphaltenes (intumescent material) as the lighter petroleum distillates, are examples of other solvents that may be employed.

With a pitch of the analysis given approximately 50 percent thereof goes into solution

with solvent oil. The solution is then filtered or otherwise separated from the insoluble portion.

The insoluble product is a brownish black powder, characterized by a high nitrogen content as compared to the crude oil, high carbon content, and by the fact that although inflammable as a powdered fuel, it does not melt but rather intumesces. Such powder is suitable for powdered or colloidal fuel, or 75 because of its high nitrogen content valuable as fertilizer. The powder is also soluble in aromatic solvents and may be used as a paint.

The dissolved portion of the pitch is relatively free of asphalt or pitch, and may be 80 processed to yield a high grade viscous lubricating oil suitable as a cylinder oil. Such oil is relatively stable at high temperatures, which due to prolonged heating and the high temperatures employed in its production 85 probably contains a material amount of polymerized bodies. Normally such extract will contain a considerable amount of petrolatum even when employing crude asphaltic base oil from which hitherto it has been impossible to 90 obtain petrolatum. Preferably such petrolatum should be extracted by one of the well known cooling processes commonly used on wax bearing crudes. The petrolatum may be further converted into paraffin wax by 95 well known processes. Thus the extract of pitch may yield petrolatum and paraffin wax even from crudes from which such products cannot normally be obtained.

The extract of the pitch is refined to produce high grade viscous lubricating oil in a manner similar to the treatment of normal lubricating distillates of petroleum. We prefer to first treat the extract with sulphuric acid of approximately 66 Baumé gravity 100 using a half pound or more of acid to a gallon of finished oil. The acid is withdrawn from the oil and the oil neutralized with caustic soda solution, and washed with water. The solvent is then distilled off, leaving a high grade lubricating oil having an exceptionally narrow range of boiling temperatures. The oil is preferably clarified by filtering through fuller's earth.

105 The penetration values herein contained are measured, as usual, by a penetrometer, a device for measuring the distance a standard needle will vertically penetrate a sample of the material when weighted with 100 grams for five seconds at 25° C. The melting point 110 of the asphalt and other products are obtained by the ring and ball method described in the Handbook of Petroleum Asphalt and Natural Gas, and Cross Bulletin No. 17 of Kansas City testing laboratory, in which a brass ring $\frac{5}{8}$ " in diameter, $\frac{1}{4}$ " deep and $\frac{3}{2}$ " wall is suspended 1" above the bottom of a beaker, and a steel ball $\frac{3}{8}$ " in diameter 115 weighing between 3.45 and 3.50 grams, a standardized thermometer, and a 600 cc. glass 120 beaker.

125

130

beaker are employed. For such tests, a sample to be tested is first melted and the ring filled with the material, any excess being removed. After cooling, the ball is then placed 5 in the center of the ring and suspended in the beaker containing water at a temperature of 5° C. The water is then heated uniformly at a rate sufficient to raise the temperature of the water 5° C. per minute. Record the 10 temperature at starting the test and every minute thereafter until the test is completed. The softening point is the temperature at which the specimen touches the bottom of the beaker. For temperatures above 99° C. 15 glycerin should be used instead of water.

Our invention is not limited to the process described herein as an example of the preferred embodiment of the invention, but various modifications may be made without departing 20 from the spirit of the invention. Our invention is of the scope set forth in the following claims:

We claim:

1. In a process of manufacturing lubricating oil, distilling petroleum oil to asphalt while avoiding decomposition through the employment of a reduced pressure during such distillation, then destructively distilling off approximately half said asphalt to form a 30 residual brittle, non-sticky pitch, and then extracting the lubricating oil constituents from the pitch with petroleum naphtha.

2. A process of treating asphalt consisting in distilling the asphalt to a pitch, extracting the lubricating constituents from the pitch with petroleum naphtha adapted to precipitate the resultant intumescent material, cooling the extract, thereby precipitating petro- 40 latum therefrom, separating the petrolatum from the extract, and distilling off the solvent from the extract.

3. A process of treating petroleum oil to produce lubricating oil, which consists in distilling the oil to asphalt while avoiding de- 45 composition by employing reduced pressure during said distillation, then distilling the asphalt to a pitch and extracting the lubricating oil constituents from the pitch with petroleum naphtha adapted to precipitate the 50 resultant intumescent material.

4. A process of producing lubricating oil from a residual petroleum asphalt comprising destructively distilling the asphalt until a residue is formed of substantially asphalt free 55 viscous oil and intumescent material, and separating the viscous oil from intumescent

material by treating the residue with a solvent of the oil which is not a solvent of the intumescent material.

5. A process of producing lubricating oil 60 from a residual petroleum asphalt comprising destructively distilling the asphalt until a residue is formed of substantially asphalt free viscous oil and intumescent material, separating the viscous oil from intumescent material by treating the residue with a solvent of the oil which is not a solvent of the intumescent material, and distilling the solvent from the viscous oil. 65

6. A process of producing lubricating oil 70 from residual petroleum asphalt comprising destructively distilling the asphalt until a near coke residue is formed containing viscous oil and intumescent material, and separating the viscous oil from the intumescent 75 material by a solvent of the viscous oil which is not a solvent of the intumescent material.

7. A process of producing lubricating oil from residual petroleum asphalt comprising destructively distilling the asphalt until approximately one half thereof remains as a substantially asphalt free residue of viscous oil and intumescent material, and separating the viscous oil from the intumescent material by a solvent of the viscous oil which is not a 80 solvent of the intumescent material. 85

8. A process of producing lubricating oil from residual petroleum asphalt comprising destructively distilling the asphalt to form a substantially asphalt free residue having a 90 melting point as determined by the ball and ring test of higher than 200 degrees Fahrenheit and a solubility of not more than 65 percent in 86 Baumé gravity gasoline, and separating viscous oil from the residue by a solvent of viscous oil which is not a solvent of the 95 remaining constituents of the residue.

9. A process of producing lubricating oil from residual petroleum comprising destructively distilling the asphalt until a substantially asphalt free near coke residue is formed containing viscous oil, and separating the viscous oil from the residue by a solvent of viscous oil which is not a solvent of the remaining constituents of the residue, the solvent being used in a ratio of at least one part of solvent to two parts of residue and not in excess of ten parts of solvent to one part of residue. 100 105
